MOLD FOR CENTRIFUGAL CASTING

Filed March 13, 1925

INVENTOR

Leon Cammen

UNITED STATES PATENT OFFICE.

LEON CAMMEN, OF NEW YORK, N. Y.

MOLD FOR CENTRIFUGAL CASTING.

Application filed March 13, 1925. Serial No. 15,273.

To all whom it may concern:

Be it known that I, LEON CAMMEN, a citizen of the United States, and resident of the borough of Manhattan, in the city, 5 county, and State of New York, have invented certain useful Improvements in Molds for Centrifugal Casting, of which the following is a specification.

The present invention deals particularly 10 with molds for centrifugally casting ingots, sheet bars, and the like, as distinguished from the more common process of centrifugally casting tubes, and specifically describes means to ensure convenient removal of the 15 castings from the mold.

The illustration shows a section of the mold at right angle to the axis of rotation.

When a tube is centrifugally cast, it naturally stays in the mold until pulled out, 20 and the problem is how to remove it therefrom rather than how to keep it in its place in the mold. But in casting ingots, sheet and plate bars, and the like, when there are more than two pieces, special attention must be devoted to means to keep 25 the pieces in place at a time when they are not held either by gravity or by centrifugal force, as e. g., when the mold slows up in spinning or stops altogether.

It is obvious that, unless special provision is made, when the mold stops spinning, the piece 1 at the top of mold 2 will fall to the bottom, and the same will probably happen to several other pieces, such as 3 and 4, and 35 possibly 5 and 6. The pieces will then pile up which will make their rapid removal difficult, and in falling may injure the mold, and themselves become bent.

It is to prevent this that the present invention has been devised. Another purpose 40 is to ensure that the cast piece may be pulled out of the mold in a convenient manner and yet without dragging it over the surface of the mold, as this latter might result in 45 scratching the surface up. Still another purpose is to ensure that the cast pieces will be located, when the mold stops spinning, in such positions that they could be conveniently pulled out of the mold by proper machinery, such as jaw grabs. For this it is 50 necessary that the cast pieces be away from the mold far enough to permit the jaws of

the grab to get hold of them, and yet not too far.

In the present invention, the partition 55 lugs 8, have their faces 90 so arranged that the casting 1, when the mold is in the position shown in the illustration, is free to move downwards, and away from the mold. To permit this, the face 90 of the partition 60 lug 8 is cut at an obtuse angle with the tangent 19 to the inside face of the mold 2 passing through the origin of 90. This feature in itself is not new, as molds for centrifugal casting of ingots and the like have 65 been so built in the past.

With this arrangement alone, however, the casting would be free to fall to the bottom of the mold, which, as has been shown above, is undesirable. To prevent this, the 70 partition lugs 8 are equipped with shoulders 11 which limit the distance through which the casting can move away from the face of the mold, and also tend to keep the casting in the proper position so that it might be 75 conveniently held by the jaws of the grab.

The particular shape of the shoulders 11 and their construction is a matter that any engineer skilled in the art may decide for himself. The shoulders may be in one piece 80 with the lugs, and made by machining or forging, or they may be welded or riveted on to the lugs. Instead of making a continuous shoulder, pins may be driven into the lug, or the lug edge may be upset here 85 and there to form the shoulder abutment. The problem is simply to provide means to keep the casting from falling away from the face of the mold to a greater extent than it is desired, and modern machine shop 90 practice affords several means to achieve this end within the confines of this invention.

As centrifugal casting of objects other than tubes is, commercially, a new art, its 95 terminology is still vague, and the parts 8 which have been referred to above as "partition lugs," are also called "projections," "shapes," "dividing bars," etc.

I claim:

1. A mold for centrifugal casting having partition lugs wherein the said lugs are of such a shape that the casting, when not held to the wall of the mold by centrifugal force

or gravity, is free to move away therefrom, and wherein the said lugs are provided with means to limit said freedom of motion of the casting away from the wall of the mold to the desired extent.

2. A mold for centrifugal casting having partition lugs wherein said lugs are pro-

vided with shoulders to keep from falling out castings which are not held by centrifugal force or gravity.

Signed in New York, in the county and State of New York, February 16, 1925.

LEON CAMMEN.
